DESIGN FOR A BILLIARD TABLE

Frank Lanza, Philadelphia, Pa.

Application August 30, 1941, Serial No. 103,115

Term of patent 3½ years

To all whom it may concern:

Be it known that I, Frank Lanza, a citizen of the United States, residing at Philadelphia, in the county of Philadelphia and State of Pennsylvania, have invented a certain new, original, and ornamental Design for a Billiard Table, of which the following is a specification, reference being had to the accompanying drawings, forming part thereof, in which:

Fig. 2 is a side elevational view of the billiard table shown in Fig. 1;

Fig. 3 is an end elevational view of the billiard table shown in Fig. 1; and

Fig. 4 is a horizontal sectional view taken on the line 4—4 of Fig. 2.

This application is a continuation in part of my prior application for design for a Billiard table, filed November 8, 1940, Serial No. D-96,432.

The dominant features of the present design are shown in full lines in the drawings.

I claim:

The ornamental design for a billiard table, as shown and described.

FRANK LANZA,
